UNITED STATES PATENT OFFICE.

WILLIAM MURRAY MORTON, OF DARVEL, SCOTLAND.

DESIGN FOR CARPET.

40,871.

Specification for Design.

Patented Sept. 6, 1910.

Application filed April 18, 1910. Serial No. 556,270. Term of patent 3½ years.

To all whom it may concern:

Be it known that I, WILLIAM MURRAY MORTON, a subject of the King of Great Britain, and resident of Hastings Square, Darvel, Ayrshire, Scotland, have invented a new, original, and ornamental Design for Carpets, of which the following is a specification, reference being had to the accompanying drawings, forming a part thereof.

The figure is a plan view of a portion of a carpet embodying my new design.

The design comprises a border the main feature of which is a treatment of peony and clematis forming a continuous growth and a body filling of ribbon work forming a diaper with sprigs at the crossings.

I claim—

The ornamental design for a carpet, as shown and described.

WILLIAM MURRAY MORTON.
